ATTORNEY

UNITED STATES PATENT OFFICE

CLIFFORD MORROW, OF CANTON, OHIO, ASSIGNEE TO THE H. H. MILLER INDUSTRIES COMPANY, OF CANTON, OHIO, A CORPORATION OF OHIO

COOLER OR HEATER

Application filed August 29, 1928. Serial No. 302,863.

This invention relates to a cooler or heater for liquids, more particularly liquid treating apparatus of the surface tubular type, one example of which is shown in Letters Patent No. 1,352,215 dated September 7, 1920, granted to Leroy S. Pfouts.

One object of the invention is to provide apparatus of this character in which the series of tubes are in connected relation to provide continuous flow surfaces thereover and from one pipe to another, whereby the liquid being treated may flow in a uniform manner downwardly to its collecting member.

Another object is to construct an apparatus of the character in which is provided between adjacent tubing flow surfaces capable of being effectively connected to either or both tubes.

Another object is to construct an apparatus of this character having improved connections between the tubing permitting the latter to expand or contract relative to each other.

Other objects of the invention will be apparent to those skilled in the art to which my invention relates from the following description taken in connection with the accompanying drawings, wherein

Fig. 1 is a vertical section on the line 1—1 of Fig. 2 of an apparatus embodying my invention.

Fig. 2 is a section on the line 2—2 of Fig. 1.

Fig. 3 is a fragmentary perspective view, enlarged.

Fig. 4 is a perspective view of the member between the tubing.

Fig. 5 is a fragmentary view showing a slightly different embodiment of the invention.

In the drawings, 1 indicates as an entirety a frame work, preferably comprising a pair of spaced members 1a, 1a. Each member 1a may be formed from bars or piping 1b, suitably connected together by braces 1c, 1c'. The opposite ends of the braces are secured to the bars 1b, in any well known manner, as by bolts 1d. The bars 1b preferably diverge from each other at their lower ends. The

lower ends of the bars may be provided with caps 1e. The caps 1e may be adjustably secured to the bars 1b.

2 indicates as an entirety the circulating means for a heating or cooling medium. The circulating means 2 is preferably arranged in sections or units, each indicated at 2'. In the illustrated construction, I provide two sections 2', one above the other, so that their pipes or conduits will be in the same vertical plane. Each unit 2' comprises a series of pipes 2a connected at their opposite ends to manifolds 2b, 2b', in any well known manner. 2a' is a member extending through each pipe 2a, and substantially from end to end thereof. 65 Each member 2a' may be formed from a hollow section of material and be provided with projecting lugs 2c to maintain the member 2a' substantially concentric to the pipe 2a, to form a relatively small or thin medium circulating space entirely around the member 2a'. The lugs 2c are preferably formed integral with and uniformly spaced around a ring 2c', which fits the pipes 2a'. Any desired number of rings 2c' may be placed on 70 and spaced along each pipe 2a' to maintain it at all points concentric to the adjacent pipe 2a. Suitable plugs or closing devices are fitted in a liquid tight manner to the opposite ends of each pipe 2a' and serve to keep 80 the heating or cooling medium from entering the pipe 2a' and filling it; and each plug may be provided with a device arranged to engage the front wall of the adjacent manifold and serve to space the end of the adjacent pipe 2a' therefrom. The manifolds 2b, 2b', are preferably provided with openings which permit access thereto, to the pipes 2a', to the interior of the pipes 2a, and to the spacers 2c'. The openings are preferably 90 closed by suitable caps 2f, which may have screw threaded engagement with the walls of the openings. By the form of construction, above described, it will be seen that a relatively small quantity of fluid is required to 95 fill the circulating space throughout the entire system, and that under such circumstances the apparatus can be run economically with efficient results. 2h, 2i, indicate the inlet and outlet connections for the heating 100

or cooling medium connected, respectively, to the lower and upper ends of one of the manifolds of each unit, such as the manifold 2b.

2h indicates a projection, such as a pipe, extending from the upper end of each manifold 2b' substantially in line with the adjacent outlet connection 2i. The projection 2h and adjacent outlet 2i fit into sockets formed in the adjacent braces 1c' and thereby serve to connect the adjacent section or unit 2' to the supporting members 1a.

3 indicates a holder for the liquid. The holder 3 is arranged above and extends longitudinally substantially from end to end of the medium circulating means 2. The holder 3 is provided with one or more series of openings 3' through which the liquid flows onto the pipes 2a of the medium circulating means 2. The holder 3 may be supported in position by any suitable means, that shown for illustrative purposes comprising a pair of yokes 3a, each having a seat 3b resting on the upper end of the adjacent manifold 2b, or 2b', a rectangular frame 3c connected in any desired manner to the opposite ends of the yokes 3a; and a plate 3d having depending flanges 3e which fit over the rectangular frame 3c. The plate 3d is formed with an opening to receive the holder 3. The walls of the opening engage with flanges or turned over edges of the holder 3 to removably support the latter in operative position. 3f indicates a cover for the holder 3.

4 indicates a flow wall or liquid guide for the liquid flowing through the opening or openings 3' in the holder 3. The purpose of this wall or guide is to control the stream or streams of liquid flowing from the opening or openings 3' and direct it or them downwardly to and against the uppermost pipe 2a.

5 indicates flow walls interposed between the pipes or tubes 2a and extending from end to end thereof and disposed in the plane of their axes. Each wall is provided along its upper or lower edge or each of said edges (preferably both edges as shown) with a relatively wide member 5a having a curvature corresponding to that of the exterior surface of the adjacent tube, whereby such member may have ample surface contact with the surface of the tube thus providing adequate soldering walls, to insure an effective soldering connection between the wall or walls and the tube. By providing two members 5a, each flow wall 5 may be soldered to both pipes in a rigid and permanent manner.

In the form of construction shown in Figs. 1, 2, 3 and 4 each flow wall is rolled from a section of copper tubing of relatively thin gage into a hollow device of substantially rectangular form in cross section with the opposite end walls of concave shape, these walls constituting the soldering members 5a and being curved to correspond to the curvature of the pipes, as already set forth. By

preference the opposite side walls of the device are of concave shape. By making the side walls of curvilinear shape and the device hollow, these walls may readily flex should the pipes 2a, due to expansion flex toward and from each other. By making the flow walls from tubing, less danger of breakage results when the circulation units are being assembled or disassembled, since the sides of these walls will yield slightly and resist strains on the soldered walls.

Fig. 5 shows a slightly different form of construction in which the flow wall 5' is rolled from a bar or otherwise formed. In this form of construction the upper and lower surfaces of the bar 5' have a curvature corresponding to that of the adjacent tubes 5a and both are preferably soldered to the pipes; and the opposite sides of the bar are concave.

In both forms of construction the opposite sides of the devices 5, 5', are of concave shape and serve as a continuation of the outer surface of one pipe to guide the liquid on to the surface of the pipe below, the surfaces of these devices being shaped in this manner to avoid or to reduce to a minimum the formation of a shoulder or rib, against which thicker portions of the liquid would lodge and hence prevent the even and uniform flow of the liquid in a film over the pipes.

To those skilled in the art to which my invention relates, many changes in construction and widely differing embodiments and applications of my invention will suggest themselves without departing from the spirit and scope thereof. My disclosures and the description herein are purely illustrative and are not intended to be in any sense limiting.

What I claim is:

1. In apparatus of the class described, the combination of a plurality of pipes for circulating a heat transfer medium, and hollow members fitting between said pipes and extending from end to end thereof, each said member having concaved sides arranged to guide the liquid from one pipe to the adjacent pipe.

2. In apparatus of the class described, the combination of a plurality of pipes for circulating a heat transfer medium, and hollow flow members between said pipes and extending from end to end thereof, one wall of each member being relatively wide and curved to fit the surface of the adjacent pipe and connected thereto.

3. In apparatus of the class described, the combination of a plurality of pipes for circulating a heat transfer medium, and hollow flow members between said pipes and extending from end to end thereof, one wall of each member being relatively wide and curved to fit the surface of the adjacent pipe and connected thereto, and the opposite side walls of said member being of curvilinear shape.

4. In apparatus of the class described, the combination of a pair of pipes disposed in parallel, superposed relation for circulating a heat transfer medium, and a member between and extending from end to end of said pipes and having curvilinear upper and lower walls fitting and connected to the opposing surfaces of said pipes and having concaved sides forming continuations of the surfaces of
10 the pipes to permit flow of liquid from the upper pipe to the lower pipe substantially uniformly.

In testimony whereof, I have hereunto subscribed my name.

15
